Primary Examiner — Sanjeev Paul(74) Attorney, Agent, or Firm — Rumit Ranjit Kanakia(57) CLAIM

I claim the ornamental design for a support pillow, as shown and described.

DESCRIPTION

FIG. 1 is a Perspective view of a support pillow showing my new design in close position;
 FIG. 2 is a Front view thereof;
 FIG. 3 is a Left-side view thereof;
 FIG. 4 is a Right-side view thereof;
 FIG. 5 is a Top view thereof;
 FIG. 6 is a Bottom view thereof; and,
 FIG. 7 is Perspective view of a support pillow showing in open position.
